US00D776142S

(12) **United States Design Patent** (10) Patent No.: **US D776,142 S**
 Kim et al. (45) Date of Patent: ** Jan. 10, 2017

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Ji-Hye Kim**, Seoul (KR); **Ji-Yoon Lee**, Seoul (KR); **Eun-Bi Kim**, Seoul (KR); **Jin-Hee Park**, Seoul (KR); **Ja-Youn Lee**, Seoul (KR)

(73) Assignee: **SAMSUNG ELECTRONICS CO., LTD. (KR)**

(**) Term: **14 Years**

(21) Appl. No.: **29/497,837**

(22) Filed: **Jul. 29, 2014**

(30) **Foreign Application Priority Data**

Jan. 29, 2014 (KR) 30-2014-0004977
 (51) LOC (10) Cl. 14-04
 (52) U.S. Cl.
 USPC D14/486
 (58) **Field of Classification Search**

Primary Examiner — Kevin Rudzinski

(74) Attorney, Agent, or Firm — Cantor Colburn LLP

(57) **CLAIM**

We claim, the ornamental design for a display screen or portion thereof with graphical user interface, as shown and described.

DESCRIPTION

The FIGURE is a front view of a display screen or portion thereof with graphical user interface, showing our new design.

The broken lines shown in the drawings illustrate the display screen and portions of the graphical user interface that form no part of the claimed design.

1 Claim, 1 Drawing Sheet
